By John H. Brumley,
His Attorney.

UNITED STATES PATENT OFFICE.

EDWARD R. RUTHSATZ, OF ST. LOUIS, MISSOURI.

SHOE AND METHOD OF MAKING THE SAME.

1,396,783.

Specification of Letters Patent. Patented Nov. 15, 1921.

Application filed November 17, 1917. Serial No. 202,634.

To all whom it may concern:

Be it known that I, EDWARD R. RUTHSATZ, a citizen of the United States, and residing at St. Louis, Missouri, have invented the new and useful Improvement in Shoes and Methods of Making the Same, of which the following is a specification.

This invention relates to shoes and methods of making the same.

10 The heel of a lady's shoe is too high to be attached in one operation. In practice, therefore, this heel is attached in sections, a base section being attached in the ordinary way, and then the top section, loaded 15 with nails, is attached to this base section. Since the nails for attaching the top section are, however, necessarily long, on account of the height of the heel, it is impossible to drive these nails completely through 20 the base section and clench them on the usual heel plate provided on the last. The result is, therefore, that these top securing nails will not be clenched at all, but will be simply inserted into the base section. This insecure 25 anchoring of the top securing nails does not secure a firm attachment of the top section to the shoe. Now on account of the shape of the heel, tapering as it does from the top to the base of the heel, necessitating, therefore, 30 that the top securing nails be anchored at a considerable distance from the end of the heel seat, any tipping force, to which the heel is necessarily subjected while in use will cause the top section to break away from the 35 base section.

One of the objects of this invention, therefore, is to provide a shoe in which the heel, and more especially the top section of a high heel, is firmly and securely attached to the 40 shoe.

Another object is to provide a novel method for firmly and securely attaching high sectional heels, and more particularly the top sections of such heels, to shoes.

45 Further objects will appear from the detail description taken in connection with the accompanying drawing, in which,

Figure 1 is a perspective view of a base section of a heel embodying this invention;

50 Fig. 2 is a section through a shoe, illustrating one step in the operation of attaching the heel to the shoe;

Fig. 3 is a section through a loaded top section;

55 Fig. 4 is a section similar to Fig. 2, but

showing the step of attaching the top section;

Fig. 5 is an enlarged detail section showing the gripping or clenching effect; and,

Fig. 6 is a perspective view of a part of a 60 shoe, showing the complete heel attached.

Referring to the accompanying drawing, 1 designates a last having a heel plate 2, upon which is mounted the shoe, comprising an upper 3, an insole 4, and an outsole 5. 65 The heel comprises a base section 6, but this base section has attached to its heel seat engaging face, an element 7, whose function it is to secure the attachment of the top section to the shoe, as hereinafter described. 70 This element comprises in this embodiment of the invention, a thin, soft steel plate, which is penetrable by the top securing fasteners, and which is attached to the heel seat of the heel by a suitable fastener 8. This 75 plate is smaller than the base section of the heel, so as to be within the contour of the fasteners attaching this base section to the shoe. In the operation of attaching a heel to a shoe, the base section is applied to the 80 shoe in the usual way, and is secured by fasteners 9, which pass through the base section and the heel seat, and which are clenched on the heel plate 2 of the last, these 85 fasteners passing outside of the contour of the plate 7, as shown in Fig. 2. The top section 10, loaded with nails 11, is now placed on the base section, and the nails 11 are driven home. These nails pass through the base section, and through the plate 7, as 90 shown in Fig. 4. The plate 7 is thick enough so as to offer considerable resistance against penetration, and the result is, therefore, that the points 12 of the nails are turned or clenched as they penetrate the plate, as 95 shown in Fig. 5. Moreover, this will serve to firmly anchor the nails by this clenching action in the heel seat of the shoe, so as to securely retain them in position. Moreover, this very clench, turning as it does the nail 100 as it passes through the plate, will serve to offer considerable resistance against direct withdrawal of the nail, and more especially the turned point, from the plate. Moreover, as shown in Fig. 5, penetration of the nail 105 through the plate will cause the formation of a bur 13, extending in the direction of movement of the penetrating nail, and as the plate is resilient, these burs will firmly but resiliently engage the sides of the nail, 110

so as to hug them close, and prevent withdrawal in the same manner that the prongs of a fish hook prevent withdrawal of the hook. This gripping action is enhanced by 5 the fact that in the formation of heel attaching nails, the edges of the nails are roughened, so as to form, in fact, corrugations extending cross-wise of the nails. Should, therefore, a nail not completely 10 penetrate the heel seat, as shown in Fig. 5, this nail will still be firmly anchored in the base section and the heel seat, so as to offer a maximum resistance against withdrawal.

It will, of course, be understood that the 15 heads of the top engaging nails or fasteners are left protruding, so as to permit spanking one of the top lifts 14, in the usual manner.

It will, therefore, be seen that the invention 20 accomplishes its objects. A shoe is produced in which the heel will be firmly and securely attached so as to offer maximum resistance against detachment, more especially of the top section. The result is obtained in a simple manner, and with only 25 slight added cost.

It is obvious that various changes may be made in the details without departing from the spirit of this invention. It is, therefore, 30 to be understood that this invention is not to be limited to the specific details described and shown.

Having thus described the invention, what is claimed is:

- 35 1. In a shoe, a heel comprising base and top sections, fasteners adapted to secure said top section, and means arranged in the path of and penetrable by said fasteners adapted to deflect the points thereof.
- 40 2. In a shoe, a heel comprising base and top sections, fasteners adapted to secure said top section, and means arranged in the path of and penetrable by said fasteners adapted to positively grip the penetrated fasteners.
- 45 3. In a shoe, a heel comprising base and top sections, fasteners adapted to secure said top section, and a plate of greater penetrating resistance than said heel sections, arranged on said base section and in the path 50 of said fasteners.
- 50 4. In a shoe, a heel comprising base and

top sections, fasteners adapted to secure said base section, fasteners adapted to secure said top section, and means arranged inside of said base section-securing fasteners but in 55 the path of said top-securing fasteners adapted to engage and retain said top-securing fasteners.

5. In a shoe, a heel comprising base and top sections, fasteners adapted to secure said 60 top section, and a penetrable clenching element arranged in the path of said fasteners.

6. The method of securing the top section of a sectional heel to the base section on a shoe, comprising interposing in the path of 65 the top-securing fasteners a penetrable element of greater penetrating resistance than the heel sections, and inserting the top-securing fasteners through the base section and the element so as to be retained by the 70 latter.

7. The method of securing the top section of a sectional heel to the base section on a shoe, comprising interposing in the path of the top-securing fasteners a penetrable 75 clenching element, and inserting the top-securing fasteners through the base section and against the element, substantially as and for the purpose set forth.

8. The method of securing the top section of a sectional heel to the base section on a shoe, comprising interposing in the path of the top-securing fasteners and between the base section and the heel seat a deflecting element, and inserting the top-securing 85 fasteners through the base section and to engage the element, substantially as and for the purpose set forth.

9. In a shoe, a base section of a sectional heel, having means combined therewith and 90 arranged in the path of the top securing fasteners adapted to deflect the points thereof.

10. In a shoe, a base section of a sectional heel, having combined therewith a difficultly penetrable plate arranged in the path of and 95 penetrable by the top securing fasteners.

11. In a shoe, a base section of a sectional heel, having a clenching plate on its heel seat engaging face.

In testimony whereof I affix my signature 100 this 14th day of September, 1917.

EDW. R. RUTHSATZ.
